United States Patent Office

Des. 196,643
Patented Oct. 22, 1963

196,643

ELECTRODE HOLDER

Robert L. Greene, Diamond Bar, Calif., assignor to
Beckman Instruments, Inc., a corporation of California

Filed Mar. 5, 1963, Ser. No. 73,823

Term of patent 14 years

(Cl. D26—1)

FIG. 1

FIG. 2

FIG. 3

FIG. 1 is a perspective view of the electrode holder showing my new design;

FIG. 2 is a side view, partially in section, of the electrode holder; and

FIG. 3 is a rear view of the electrode holder.

I claim:

The ornamental design for an electrode holder, substantially as shown.
